UNITED STATES PATENT OFFICE.

**PARK E. WELTON, OF CUYAHOGA FALLS, OHIO, ASSIGNOR TO THE TIRE PRODUCTS
MANUFACTURING COMPANY, OF SALISBURY, NORTH CAROLINA, A CORPORATION
OF NORTH CAROLINA.**

DESIGN FOR A TIRE TREAD.

Application filed January 27, 1923. Serial No. 5,018. Term of patent 7 years.

To all whom it may concern:

Be it known that I, PARK E. WELTON, a citizen of the United States, residing at Cuyahoga Falls, in the county of Summit, State of Ohio, have invented a new, original, and ornamental Design for Tire Tread, of which the following is a specification, reference being had to the accompanying drawing, forming a part thereof.

In said drawing, Fig. 1 is a plan view; and Figs. 2 and 3 are cross-sectional views on lines indicated at 2—2 and 3—3 in Fig. 1.

I claim:

The ornamental design for a tire tread substantially as shown.

PARK E. WELTON.
